UNITED STATES PATENT OFFICE

158,473

COMBINED FOLDING TABLE, SEATS, AND CABINET THEREFOR

Herman Lahr, Grosse Pointe Woods, Mich., assignor to The Bela Company, Detroit, Mich., a corporation of Michigan

Application October 6, 1948, Serial No. 148,986

Term of patent 14 years

(Cl. D33—14)

To all whom it may concern:

Be it known that I, Herman Lahr, a citizen of the United States of America, residing at Grosse Pointe Woods, in the county of Wayne and State of Michigan, have invented a new, original, and ornamental Design for a Combined Folding Table, Seats, and Cabinet Therefor, of which the following is a specification, reference being had to the accompanying drawing, forming a part thereof.

The single figure is a perspective view of my new design for a combined folding table, seats, and cabinet therefor.

I claim:

The ornamental design for a combined folding table, seats, and cabinet therefor, substantially as shown.

HERMAN LAHR.
